CLAIM

The ornamental design for a vehicle seat assembly, as shown and described.

DESCRIPTION

FIG. 1 is a perspective view taken from a front, left side of a vehicle seat assembly according to my design;
FIG. 2 is a perspective view taken from a rear, right side thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a perspective view taken from a front, left side of the vehicle seat assembly of FIG. 1 shown on a motorcycle shown in dotted lines;

FIG. 10 is a perspective view taken from a rear, right side thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The dashed broken lines in the drawings illustrates the environment of the vehicle seat assembly which forms no part of the claimed design, and the dotted-dashed lines illustrates the unclaimed boundaries of surfaces of the claimed design.
